BLOWPIPE

Wilgot J. Jacobsson, Plainfield, and Samuel R. Oldham, Newark, N. J., assignors to Oxweld Acetylene Company, a corporation of West Virginia

Application November 4, 1939, Serial No. 302,830

5 Claims. (Cl. 158—27.4)

This invention relates to cutting and welding blowpipes generally, and has particular reference to improvements in deseaming, heat treating, cutting, and welding blowpipes in which a mixture of combustion-supporting gas such as oxygen, and fuel gas such as acetylene, is used to maintain a flame for heating material when the blowpipe is used for welding and heat treating purposes, and in which a jet of oxygen is used with the preheating gases when the blowpipe is employed for cutting and deseaming purposes.

A flashback is generally known as a recession of the flame inside the blowpipe, where it continues to burn. A flashback is very undesirable, because, if allowed to continue, it will burn and ruin the blowpipe in a short time. If the rate at which the gas mixture leaves the blowpipe tip always exceeds the rate of propagation of the flame, flashbacks ordinarily will not occur. Accordingly, it is important to maintain at the blowpipe tip a rate of mixed gas travel which is greater than that of the flame propagation.

Since combustion-supporting gas is usually available at higher pressure than fuel gas, it is customary to use the flow of the combustion-supporting gas to aspirate the fuel gas, to effect the mixing of the gases, and to impart to the gas mixture the necessary rate of travel at the blowpipe tip. When a blowpipe is used with a combustion-supporting gas at substantially constant pressure, a change in fuel gas pressure may affect the composition of the gas mixture which the blowpipe delivers, as well as the rate of propagation of the mixed gases. The efficiency and resistance of a low pressure blowpipe to flashback, therefore, are responsive to the fuel gas pressure.

Furthermore, it is a well-known fact that a low pressure type blowpipe, so called because the fuel gas is supplied at a low pressure (less than 1 lb./sq. in.) will operate satisfactorily with fuel gas at medium pressure (1 lb./sq. in. or greater), if properly adjusted. However, great care is required in adjusting the fuel gas inlet valve when making the changeover, because of the sensitivity of the blowpipe to fuel gas pressure. The best efficiency is obtained when a small change in the amount of oxygen produces a corresponding change in the amount of acetylene drawn into the gas mixture. Such adjustment takes valuable time and is not always satisfactory.

One object of the invention is, therefore, to provide a blowpipe having high efficiency and flashback resistant characteristics, which may

be used with fuel gas at either medium or low pressure with equal precision. Another object is the provision of a blowpipe which may be used with fuel gas at either medium or low pressure without substantial alteration of its high resistance to flashback. A further object is the provision of such a blowpipe in a form which does not require the removal and substitution of parts, or careful adjustment, when changing from fuel gas at one pressure to that at another. A still further object is to provide a cutting and welding blowpipe that is simple in construction and economical to manufacture, efficient and effective in operation, and capable of operation with either low or medium pressure acetylene with a high degree of flashback resistance in either case.

Other objects and novel features of the invention will be apparent from the following description taken with the accompanying drawing, in which:

Fig. 1 is a fragmentary view in longitudinal cross section of a machine cutting blowpipe embodying features of the invention;

Fig. 2 is an enlarged view in cross section taken on a line corresponding to line 2—2 of Fig. 1; and

Fig. 3 is a fragmentary view in longitudinal cross section of a modification.

Considered from the points of view of construction and operating principles, all oxy-acetylene blowpipes are of two general types, low pressure and medium pressure. The distinction refers to the acetylene pressure range required for operation. Acetylene supplied at pressures of less than 1 pound per square inch is designated as low pressure, and from 1 to 15 pounds per square inch as medium pressure. Low pressure blowpipes are capable of using acetylene from low pressure generators, medium pressure generators, or cylinders. However, the change from low pressure to medium pressure is generally accompanied by a loss of efficiency and a loss of flashback resistance, as well as a loss of time. For medium pressure blowpipes, the acetylene pressure must be more than 1 pound per square inch. Medium blowpipes are capable of use with medium pressure generators or cylinders, but not with low pressure generators.

Low pressure blowpipes make use of what is known as the injector principle. Oxygen at high velocity passes through a small opening in the injector nozzle, producing a suction effect which draws acetylene into the oxygen stream. One advantage of this type of construction is that

small changes in the amount of the oxygen flowing will produce a corresponding change in the amount of acetylene aspirated, so that the proportions of the two gases remain substantially constant while the blowpipe is in operation.

In the present invention we secure the desirable advantages and features of a blowpipe of the low pressure type, while at the same time providing a blowpipe that is capable, through automatic or quick manual changeover valve means, of utilizing either medium pressure acetylene or low pressure acetylene with equal precision relative to efficiency and flashback resistance. Briefly, this desirable result is accomplished by the use of separate valve means associated with the fuel gas delivery passage in the blowpipe, and independent of the combustion-supporting gas supply conduit, for so restricting the flow of fuel gas that fuel gas supplied at medium pressure is reduced within the delivery passage, before delivery adjacent to the injected combustion supporting gas stream, to the proper low pressure for aspiration by the combustion-supporting gas. Such valve means is preferably a throttling valve adapted to lower the acetylene pressure around the injector sufficiently to produce improved flashback resistance when the blowpipe is supplied with acetylene at medium pressure; said throttling valve being adapted also, when properly adjusted manually or automatically, to allow free substantially unrestricted flow of low pressure acetylene for low pressure operation with high resistance to flashback.

The throttling valve may be automatically or manually operated, an example of a manually operated throttling valve being shown in Figs. 1 and 2 of the drawing, and an automatically operated acetylene throttling valve being shown in Fig. 3 of the drawing. The automatically operated valve preferably is a small regulator built into the rear body of the blowpipe, whereas the manually operated valve is preferably a restrictive orifice valve with one orifice of such size as to give sufficient throttling over the entire range of possible pressures and consumptions to give improved flashback resistance on medium pressure acetylene, and another orifice large enough to give excellent flashback resistance and sufficient acetylene flow for low pressure operation.

Referring to the drawing, and to Figs. 1 and 2 in particular, the cutting blowpipe consists of a body portion B comprising an elongated tubular shell 4 within which is disposed a casting 5, there being a ferrule 6 associated with the forward end of the body portion and a valve block 7 associated with the rearward end thereof. The valve block 7 has attached to it a nipple 8 to which the cutting oxygen supply pipe or tube may be attached in any desired manner.

The valve block 7 is provided with a cutting oxygen passage 9 having a manually controlled valve 10 associated therewith, the cutting oxygen passage 9 being in series with a cutting oxygen passage 11 in the casting 5, which delivers cutting oxygen to a central cutting oxygen passage in the blowpipe tip T, which is secured to the ferrule 6 by a coupling nut 12 in a well-known manner.

The supply of heating oxygen is controlled by a manually operated valve 13 associated with an oxygen supply passage or conduit 14 in the valve block 7, the supply of heating oxygen being delivered to an injector nozzle N through a heating oxygen delivery tube 15, which is connected at the rear end thereof with the supply passage 14 through a cross passage (not shown).

The nozzle N is provided with an axial oxygen passage 16 terminating in a restricted central outlet 17 which acts to project a fine stream of high velocity heating oxygen into the gas mixing passage or chamber 18 in the casting 5. The gas mixing passage 18 is provided with a flared outer portion 19 which acts to further mix the gases, which are thereupon delivered to a series of heating gas passages in the tip T arranged around the central cutting oxygen passage therein.

Mixing of the acetylene and oxygen gases takes place in the passage 18, as pointed out above, the acetylene being delivered thereto through a fuel gas supply conduit, including a supply passage 20 having a valve chamber C in the valve block 7, and a fuel gas delivery passage 21 in the casting 5 and the valve block 7, the latter including an elongated conduit 22 surrounding the passages of the nozzle N and the oxygen delivery tube 15. The fuel gas supply passage 20 is provided with a manually controlled valve 22 associated with the valve block 7. Thus, as oxygen passes through the small orifice 17 of the injector nozzle N, its velocity is increased and a suction is produced that draws acetylene through the conical way 23 surrounding the nozzle N and into the mixing passage 18, through which the two gases then pass together and are delivered to the expanding passage 19, which insures thorough mixing of the heating oxygen and acetylene so that the mixture issuing from the blowpipe tip T will burn properly.

The oxy-acetylene flame is produced at a series of openings in the blowpipe tip or nozzle which surround the larger central cutting oxygen orifice, as pointed out above. As is well understood by those skilled in the art, the function of the oxy-acetylene heating flames in a cutting blowpipe such as shown in the drawing is to preheat the metal that is to be cut. The use of a number of preheating flames, rather than a single one, makes it possible to change the direction of the cut as desired. In a blowpipe designed for welding or heat treating only, the oxygen and acetylene for the heating flame are mixed in the same manner as in the machine cutting blowpipe described herein.

Associated with the acetylene delivery passage 21 in the valve block 7 is a throttling valve M, preferably in the form of a hollow cock 24 having a large opening 25 and a small opening 26 in its periphery, these openings being angularly spaced about 105 degrees apart. The openings 25 and 26 are disposed in such angular relation that by turning the valve M, one opening or the other may be presented alternatively in the passage 21 for controlling the flow of fuel gas therethrough.

The hollow cock 24 preferably is provided with a stem 27, to the outer end of which is secured a handle 28 in the form of a cup enclosing the cylindrical boss 29 on the valve block 7, and the packing gland nut 30, in spaced relation thereto. Gas leakage in the assembly is prevented by a packing 31 which is urged into sealing association with the cock 24 by a compression spring 32 acting through a washer 33.

It will thus be seen that in the gas delivery passage 21 are provided a valve M having a large opening 25 and a small opening 26 in its periphery adapted to register alternatively with the gas delivery passage 21 to vary the rate of fuel gas flow through the delivery passage, together with means 27 for turning said valve to cause either the large hole 25 or the small hole

26 therein to register with the gas delivery passage 21, and means 31 sealing the valve cock 24 in the gas delivery passage 21 to prevent gas leakage past said turning means.

Although the machine cutting blowpipe illustrated is of the low pressure type wherein a combustion-supporting gas is caused to aspirate and mix with a low pressure fuel gas to maintain a flame, the valve means M associated with the fuel gas delivery passage 21 is such that when the small orifice 26 is disposed therein, the flow of fuel gas is so restricted by said small orifice 26 that fuel gas supplied to the blowpipe at medium pressure is reduced within the delivery passage 21 to a low pressure for aspiration by the combustion-supporting gas issuing from the injector nozzle N.

When it is desired to use the machine cutting blowpipe with a low pressure acetylene supply, the valve M is turned so that the large orifice 25 is presented in the fuel gas delivery passage 21. Sufficient unrestricted acetylene flow is thus provided for low pressure operation. It will thus be seen by those skilled in the art that there is provided a blowpipe having the desirable operating characteristics and high flash-back resistance of a low pressure blowpipe, yet capable of precision use with fuel gas supplied at either medium pressures or low pressures.

Referring to Fig. 3 of the drawing, there is illustrated a blowpipe P of the low pressure type wherein a combustion-supporting gas is caused to aspirate and mix with a low pressure fuel gas to maintain a flame, substantially in the manner pointed out above in connection with the machine cutting blowpipe shown in Figs. 1 and 2. The blowpipe P comprises a valve block 37 having an oxygen supply passage 38 and a separate acetylene supply passage 39. These passages are provided with control valves 40 and 41, respectively, as well as with conventional connections 42 and 43 for the oxygen and fuel gas supply pipes or tubes, respectively.

The valve block 37 also has associated therewith an automatic fuel gas pressure responsive regulator valve A. The automatic pressure responsive valve A preferably comprises a valve member 44 on a valve stem 45 which is secured by a head bolt 46 to a diaphragm D in the central portion thereof, the outer periphery of the diaphragm D being secured within a cylindrical boss 47 of the valve block 37 against an annular internal shoulder by a cap screw 48 having a vent 59. The position of the valve 44 in the valve chamber E relative to a valve seat 49 is controlled by a compression spring 50 disposed between the cap 48 and the diaphragm D, there being a locating and pressure distributing plate 51 for the spring 50 associated with the diaphragm D and secured in place by the bolt 46.

In operation, with the force of the spring 50 adjusted so that the valve 44 is properly spaced from the valve seat 49 for precision operation of the blowpipe with low pressure acetylene, when the blowpipe is connected to an acetylene source at medium pressure, the diaphragm D acts in response to the increase in the pressure of the fuel gas supply to close or restrict the effective opening of the automatic valve A so that fuel gas is stepped down from medium pressure to low pressure on the discharge side of the regulator for aspiration by the combustion-supporting gas. The flow of fuel gas is through the connection 43, valve 41, supply passage 39, valve A, and fuel gas delivery passage 52.

It will thus be seen by those skilled in the art that the blowpipe shown in Fig. 3 of the drawing operates in a manner substantially similar to that described previously in connection with the manually operated throttling valve, but requires no attention on the part of the operator. That is to say, all of the advantages and desirable characteristics inherent in a blowpipe of the low pressure type are obtained by the invention, whether the blowpipe is operated on either low pressure or medium pressure fuel gas. Blowpipes constructed according to the present invention are very efficient and effective in operation, and highly resistant to flashback.

While the invention has been shown and described in detail, it is not to be limited to the exact form of construction described and illustrated, as it is obvious that various changes may be resorted to without departing from the spirit of the invention.

We claim:

1. In a blowpipe, the combination with an injector for injecting a combustion-supporting gas stream, passage means for delivering fuel gas adjacent to such injected combustion-supporting gas stream, said injector and said passage means being so designed that fuel gas at low pressure will be aspirated by combustion-supporting gas at relatively high pressure to provide a properly proportioned combustible gas mixture, separate gas-supply conduits for said combustion-supporting gas and said fuel gas, respectively, and a control valve in each of said conduits; of valve means in said fuel-gas supply conduit adapted to maintain at low pressure the fuel gas delivered to said passage means, said last-named valve means being operable either to permit the substantially unrestricted flow therethrough of fuel gas supplied thereto at low pressure, or to reduce to low pressure fuel gas supplied thereto at medium pressure.

2. In a blowpipe of the low pressure type, wherein a combustion-supporting gas at high pressure is caused to aspirate and mix with a low pressure fuel gas to provide a combustible mixture and maintain a flame, the combination with means providing a mixing chamber, an injector for injecting a combustion-supporting gas stream into said mixing chamber, passage means for supplying fuel gas to said chamber, and separate supply conduits for the combustion-supporting gas and fuel gas, at least the fuel gas supply conduit having a control valve therein; of valve means in said fuel gas supply conduit and independent of said combustion-supporting gas conduit adapted to maintain at low pressure the fuel gas delivered to said mixing chamber, said last-named valve means being operable either to permit the substantially unrestricted flow therethrough of fuel gas supplied thereto at low pressure, or to reduce to low pressure fuel gas supplied thereto at medium pressure.

3. In a blowpipe, the combination with an injector for injecting a combustion-supporting gas stream, passage means for delivering fuel gas adjacent to such injected combustion-supporting gas stream for aspiration thereby, and separate supply conduits for supplying combustion-supporting gas and fuel gas, at least the fuel gas conduit having a control valve therein; of a manually controlled valve associated with said fuel gas supply conduit and independent of said combustion-supporting gas conduit, said last-named valve having a large opening for the substantially unrestricted flow therethrough of

low pressure fuel gas, and a small opening for medium pressure fuel gas, said last-named valve being operable to register said openings alternatively with said fuel gas supply conduit, said small opening being adapted to reduce to low pressure fuel gas supplied thereto at medium pressure for aspiration by said high pressure combustion-supporting gas.

4. In a blowpipe, the combination with an injector for injecting a combustion-supporting gas stream, passage means for delivering fuel gas adjacent to such injected combustion-supporting gas stream, said injector and said passage means being so designed that fuel gas at low pressure will be aspirated by combustion-supporting gas at relatively high pressure to provide a properly proportioned combustible gas mixture, and separate gas supply conduits for said combustion supporting gas and said fuel gas, respectively, at least the fuel gas supply conduit having a control valve therein; of a hollow cock valve in said fuel gas supply conduit, said cock valve having a large opening for the substantially unrestricted flow of low pressure fuel gas, and a small opening for medium pressure fuel gas adapted to register alternatively with said fuel gas supply conduit, said small opening being adapted to reduce to low pressure fuel gas supplied thereto at medium pressure; means for turning

5 said cock valve to cause either said small opening or said large opening to register with the gas supply conduit; means for maintaining said cock valve in place in said fuel gas supply conduit; and means sealing said cock valve in said fuel gas supply conduit to prevent leakage past said turning means.

5. In a blowpipe, the combination with an injector for injecting a combustion-supporting gas stream, passage means for delivering fuel gas adjacent to such injected combustion-supporting gas stream for aspiration thereby, and separate supply conduits for the combustion-supporting gas and the fuel gas; of an automatic fuel 10 gas pressure responsive pressure regulating valve associated with said fuel gas supply conduit and independent of said combustion-supporting gas conduit, said pressure regulating valve being adjusted to maintain a low pressure on the discharge side thereof, thereby so controlling the flow of fuel gas that fuel gas supplied at medium pressure is reduced within said 15 pressure regulating valve to low pressure and delivered to said passage means for aspiration by the high pressure combustion-supporting 20 gas.
